MIXING FLUIDS OF DIFFERENT TEMPERATURES AND DENSITIES

Alfred V. Sims, New York, N. Y.; Alfred William Sims, executor of said Alfred V. Sims, deceased

Application August 3, 1940, Serial No. 350,250

10 Claims. (CL. 261—77)

This invention relates to the mixing of a fluid of high temperature and low density, such as steam, with a fluid of low temperature and high density, such as water.

The main object of the invention is to accomplish mixtures as referred to without noise such as is usually or frequently incidental thereto. This is accomplished according to the present invention by causing a current of the fluid of high temperature and low density, such as steam, below the surface of the other fluid, such as water, and drawing or inducing the flow of the water into the steam gradually i. e. in such increments as to gradually condense the high temperature, low density fluid (steam), so that no noise is caused. The heat of the higher temperature fluid (steam) is thus imparted to the low temperature fluid (water).

It is a further object of the invention, while accomplishing the ends as indicated, to effect an efficiency by passing the high temperature fluid, such as steam, below the surface of the low temperature fluid, such as water, in a stream or current through a heat conducting conduit in one direction and reversing the direction of flow of said stream so that it passes in the opposite direction, in contact with the outside of said conduit, and induces a flow of the low temperature fluid into such stream.

An important use of the invention is to utilize steam, usually waste steam, to heat the condensate from main and auxiliary engines, in the hot well or filter box before the condensate is forced into the boiler, or into another heater en route to the boiler. The invention is however applicable to many other uses.

Other and ancillary objects of the invention will appear hereinafter.

In the accompanying drawing which illustrates the invention:

Fig. 1 is a side elevation, with the hot well in section, of a hot well and heater embodying the invention;

Fig. 2 is an axial section, on an enlarged scale of the heater;

Fig. 3 is a bottom plan view of one of the bells or petticoats of the heater of Fig. 2;

Fig. 4 is a bottom plan view of the heater of Fig. 5;

Fig. 5 is an axial section of a modified form of heater embodying the invention; and

Fig. 6 is a top plan view of one of the bells or petticoats of the heater of Fig. 5.

Referring to the drawing and first to Figs. 1 to 3 inclusive, the hot well A (see Fig. 1) con-

tains the water B to be heated and into the water is immersed the device C by means of which the steam and water are noiselessly mixed to heat the latter, such device being supplied with steam through the pipe D.

The device C comprises the base or pot portion 1 within which enters the lower end of the thin, metal, heat-conducting conduit 2. The conduit 2 is spaced from the bottom wall 3 of the pot and also from the side wall 4 of the pot. The top baffle or cap piece comprises a curved upper top 5 with a central, tubular hub 6 and a screw-threaded nipple 7 by which the end of the steam supply pipe is secured to the device. The nipple 7 has a central hub portion 8 supported from the circumferential wall of the nipple by suitable arms or ribs having apertures between them for the passage of the steam.

Telescoped within the hub 6 is the upper end 20 of the conduit 2 and radial ribs or flanges 9 secured to the top 5 of the cap piece and to the hub 6 serve to strengthen the structure and also form a bearing for the flaring petticoat 10, the upper circumferential edge 11 of which fits into notches 12 in the lower edges of the flat ribs 9 spaced about the circumference of the cap piece. From the inner side of the petticoat 10 extend the flat ribs 13 spaced about the circumference of the petticoat so as to provide apertures therebetween for the passage of fluid, and the inner ends of such ribs bear against the conduit 2 so as to firmly space and support the petticoat. In the bottoms of the ribs 13 are notches 14 within which enters the upper circumferential edge 15 of the flaring petticoat 15 which has the inwardly projecting circumferentially-spaced flat ribs 16, similar to the ribs 14, bearing against the conduit 2.

In the lower edges of the rib 16 are the notches 17 within which enter the upper edge of the circumferential wall of the flared petticoat 18 having the inwardly extending circumferentially-spaced flat ribs 19, similar to the ribs 14, bearing against the conduit 2.

In the lower edges of the ribs 19 are the notches 20 within which enter the upper circumferential edge of the flaring petticoat 21 which has the inwardly extending circumferentially-spaced flat ribs 22, similar to the ribs 14, and bearing against the conduit 2. In the lower edges of the flat ribs 22 are notches 23 within which fit the upper edge of the side wall 4 of the pot or base 1. Also the side wall 4 has the circumferentially-spaced projections 24 bearing against the conduit 2. Also the side and bottom walls of the base portion 1

may have the circumferentially-spaced ribs 25 which bear against the outside of the conduit 2 and also extend beneath the end of that conduit. There is thus assuredly provided within the pot or base 1 spaces or apertures through which steam issuing from the lower end of the conduit 2 may pass into the pot and upwardly between the lateral sides of the pot and the conduit.

It will be seen that the petticoat 15 extends within the petticoat 10, the petticoat 18 extends within the petticoat 15 and that the petticoat 21 extends within the petticoat 18, and that there is formed between the petticoat 10 and the petticoat 15 an annular orifice 26 whereby the water may be induced into the steam stream. Similarly there is an annular orifice 27 between the petticoats 15 and 18 and a similar orifice 28 between the petticoats 18 and 21. Between the petticoat 21 and the flange 29 extending from the side walls of the pot 1 is an orifice 30 through which the water may enter the conduit. The top cap 5 and the base portion 1 are held together with the petticoats 10, 15, 18 and 21 clamped between them, as shown particularly in Fig. 2, by a bolt 31 extending centrally through the conduit 2, through the hub 8 of the cap piece 5 and the bottom wall 3 of the base pot portion 1, such bolt having a nut 32 on its end beneath the wall 3 of the base portion and the nut 33 screwed upon it outside of the hub 8, there being introduced between the nut 33 and the hub 8 a spring washer 34 or other suitable resilient device whereby the parts are resiliently secured together and are firmly pressed together at all times so that the parts may not become loose or develop any vibrations which would tend to produce noise or other deleterious effects. Screwed upon the bolt 31 outside the nut 33 is a jam nut 35.

It will be observed that by the construction shown the parts of the apparatus are firmly held together with a substantially continuous pressure irrespective of vibration and that no pressure comes on the thin conduit 2, the clamping pressure between the cap piece 5 and the pot 1 being borne by the engaging petticoats and ribs between the top and base pieces as described.

It will be observed that the orifices 26, 27, 28 and 30 progressively decrease in width in the order mentioned or conversely increase in diameter inversely to the order mentioned. Also there are annular orifices between the upper ends of the petticoats 10, 15, 18 and 21 respectively and the thin, central metal conduit 2, also an annular orifice between the upper end of the pot wall 4 and the conduit 2, these orifices progressively increasing in width from that between the wall 4 and the conduit 2 to that between the upper edge of the petticoat 10 and the conduit 2.

In its operation, the device as shown in Fig. 2 is immersed in the liquid to be heated by steam as shown in Fig. 1. The steam passes in through the nipple 7 into the thin, metal conduit 2, the steam then passing through the conduit to the bottom thereof passed outwardly between the side wall of the pot and the lower end of the tube, and along the outer side of the conduit 2 and through the annular orifice between the upper edge of the pot side wall and the conduit. As the steam passes from this orifice it acts to force the water and steam through the somewhat larger orifice between the upper edge of the petticoat 21 and the conduit, and at the same time induces water to flow from the outside of the interior of the petticoat through the orifice 30. The action of the

steam being continuous, it will cause a steady flow through the orifice 30.

Likewise the passage of the hotter water mixed with the steam issuing from the orifice between the upper edge of the petticoat 21 and the conduit 2 will force the mixed water and steam through the orifice between the upper edge of the petticoat 18 and the conduit, which is somewhat larger than the orifice at the upper edge of the petticoat 21, and will induce an inflow of water at the orifice 28, such orifice being somewhat larger than the orifice 29. The mixture of steam and water will, in like manner, flow from the annular orifices, progressively increasing in size, between the upper edges of the petticoats 18, 15 and 10, the inflow of water being respectively induced at the annular orifices 27 and 26 which progressively increase in width. The mixed steam and water finally passes through the orifice between the upper edge of the petticoat 10 and the conduit 2 against the curved top 5 of the cap piece, which is of greater radial extent than the petticoats, and is deflected outwardly and downwardly at an oblique angle to the device by such top through an annular orifice between the edge of the top piece and the top of the petticoat 10 into the body of water in which the device is immersed, the steam being condensed before it reaches the cap cover 5.

The noise and commotion of steam projected into colder water is caused by the impact of the walls of the bubbles which are formed. By the passage of the high temperature steam, however, through the conduit 2, a film of steam is formed upon the outside of that conduit which prevents the walls of any bubbles formed from impacting by forming a cushion for the approximately hemispherical globules of steam which give up their heat through the surfaces in contact with the water.

It will be seen that the greater the steam pressure in the central conduit the greater will be the amount of water that will be inducted into the device through the water intake orifices as referred to. The present device therefore, instead of following the noisy methods of heating water by steam, by forcing steam into the water to effect heating through the steam condensation, operates by inducing the water to enter the steam and thus does away with any noise of operation.

Referring now to Figs. 4 to 6 inclusive, there is therein shown a device similar to that of Figs. 2 and 3, the main difference being that the device of Figs. 4 to 6 is adapted to be attached on the end of a pipe that is to supply the steam to be condensed, and the direction of the flow of the steam and the ingoing condensing water are not reversed as in the case of the device of Fig. 2. The device of Figs. 4 to 6 therefore may lack such of the elements of efficiency that such action in the device of Fig. 2 affords. The advantage of the device of Figs. 4 to 6, however, comes from its decreased size in diameter which permits it to be installed in many places that would not accommodate the device of Fig. 2.

The device of Figs. 4 to 6 comprises a steam supply pipe 36 secured to an end member 37 comprising the outer cylindrical part having a central hub 38 supported from the cylinder by means of spokes 39 with apertures between them through which the fluid may pass. At the end of the cylindrical portion is an annular ridge 40 fitting into notches 41 in flat ribs 42 extending inwardly from the inner walls of the flared petticoat 43 which has an inwardly extending flange

44 with a central aperture 45. Also there is an annular orifice 46 between the member 37 and the wide end of the petticoat 43. The petticoat 43 has an annular ridge 47 fitting into notches 48 in the ribs or webs 49 which extend inwardly from the flared petticoat 50 and are spaced circumferentially. Also the petticoat 50 has an inwardly extending flange 51 with a central aperture 52 and a circular ridge 53 fitting into notches 54 in the circumferentially spaced webs 55 extending inwardly from the flared petticoat 56 having an inwardly extending flange 57 with a central aperture 58. The petticoat 53 also has a circular ridge 59 fitting into notches 60 in circumferentially spaced webs 61 extending inwardly from the flared petticoat 62 having an inwardly extending flange 63 with a central aperture 64. The petticoat 62 also has a circular ridge 65 fitting in notches 66 in circumferentially spaced ribs 67 extending inwardly from the flared petticoat 68 having an inwardly extending flange 69 with a central aperture 70. Also the petticoat 68 has a circular ridge 71 fitting into notches 72 in the circumferentially spaced ribs 73 extending between the outer rim 74 of the end member of the device, and a central hub 75. The parts are clamped together by a bolt 76 passing through the hub 38 and having a nut 77 screwed upon it outside of the hub, and also passing through a hub 75 and having a nut 78 screwed upon it outside the hub 75, a spring washer 79 being interposed between the nut 78 and the hub 75 to resiliently hold the parts together for the reasons as explained in connection with the structure of Fig. 2. A jam nut 80 is provided outside the nut 78.

It will be seen that there are annular orifices 81, 82, 83 and 84 between the petticoats and the end member, such orifices increasing in width progressively in the order named, and that there is a larger annular orifice 85 between the petticoats 68 and its adjacent end member.

It will also be observed that the orifices in the flanges 44, 51, 51, 63, 73 and 74 and in the end member progressively increase in size in the order mentioned.

The steam admitted through the member 37 induces inflow of water through the orifice 46. This mixture of steam and water then passes through the central opening 45 which in turn induces inflow of water through the orifice 81. This action continues as the steam and water flows through the central apertures and induces inflow of water at the periphery of the flanged petticoats until condensation has been completed. The condensed water and condensate will then commence to flow out of the orifices at the circumference of succeeding petticoats instead of the water entering at such points.

While the invention has been illustrated in what are considered its best applications it may have other embodiments without departing from its spirit and is not therefore limited to the structures shown in the drawing.

What I claim is:

1. A device for mixing fluids, adapted for immersion in a fluid bath, comprising in combination a plurality of flared petticoats each having a central opening and means for clamping said petticoats together including a central rod passing through said central openings, said openings forming a central passage for a stream of one fluid to be mixed and means for supplying said stream of fluid to said passage, said petticoats flaring outwardly in the direction oppo-

site the flow of said stream and said petticoats having openings between them through which the immersing fluid may enter said stream.

2. A device for mixing fluids, adapted for immersion in a fluid bath, comprising in combination a plurality of flared petticoats each having a central opening and means for clamping said petticoats together including a central rod passing through said central openings, said openings forming a central passage for a stream of one fluid to be mixed and means for supplying said stream of fluid to said passage, said petticoats flaring outwardly in the direction opposite the flow of said stream and said petticoats having openings between them through which the immersing fluid may enter said stream, the said openings between said petticoats being of different conductive capacities which progressively increase in the direction of said stream.
- 20 3. A device for mixing fluids, adapted for immersion in a fluid bath, comprising in combination a plurality of flared petticoats each having a central opening and means for clamping said petticoats together, said openings forming a central passage for a stream of one fluid to be mixed and means for supplying said stream of fluid to said passage, said petticoats flaring outwardly in the direction opposite the flow of said stream and said petticoats having openings between them through which the immersing fluid may enter said stream, said petticoats having internal ribs, the end of each petticoat bearing against a rib of an adjacent petticoat.
- 35 4. A device for mixing fluids, adapted for immersion in a fluid bath, comprising in combination a plurality of flared petticoats each having a central opening and means for clamping said petticoats together including a central rod passing through said central openings, said openings forming a central passage for a stream of one fluid to be mixed and means for supplying said stream of fluid to said passage, said petticoats flaring outwardly in the direction opposite the flow of said stream and said petticoats having openings between them through which the immersing fluid may enter said stream, said petticoats having internal ribs, an end of each petticoat bearing against a rib of an adjacent petticoat.
- 40 5. A device for mixing fluids, adapted for immersion in a fluid bath, comprising in combination a plurality of flared petticoats each having a central opening and means for clamping said petticoats together including a central rod passing through said central openings, said openings forming a central passage for a stream of one fluid to be mixed and means for supplying said stream of fluid to said passage, said petticoats flaring outwardly in the direction opposite the flow of said stream and said petticoats having openings between them through which the immersing fluid may enter said stream, said petticoats having internal ribs, an end of each petticoat bearing against a rib of an adjacent petticoat.
- 45 6. A device for mixing fluids, adapted for immersion in a fluid bath, comprising in combination a plurality of flared petticoats each having a central opening and means for clamping said petticoats together including a central rod passing through said central openings, said openings forming a central passage for a stream of one fluid to be mixed and means for supplying said stream of fluid to said passage, said petticoats flaring outwardly in the direction opposite the flow of said stream and said petticoats having openings between them through which the immersing fluid may enter said stream, and a spring about said rod and resiliently pressing said petticoats together.
- 50 7. A device for mixing fluids, adapted for immersion in a fluid bath, comprising in combination a central pipe, means for introducing a stream of fluid into one end of said pipe, means at the other end of said pipe for receiving fluid from said pipe and turning it backwardly into a passage formed between the outside of said pipe and a plurality of petticoats, a plurality of petticoats surrounding said pipe and separated therefrom to form said passage therebetween, said petticoats having openings between them

through which the immersing fluid may enter said passage and means securing said petticoats together.

7. A device for mixing fluids, adapted for immersion in a fluid bath, comprising in combination a central pipe, means for introducing a stream of fluid into one end of said pipe, means at the other end of said pipe for receiving fluid from said pipe and turning it backwardly into a passage formed between the outside of said pipe and a plurality of petticoats, a plurality of petticoats surrounding said pipe and separated therefrom to form said passage therebetween, said petticoats having openings between them through which the immersing fluid may enter said passage and an outwardly flared baffle member of greater radial extent than said petticoats receiving fluid from said passage and discharging it into an immersion bath at an oblique angle to the device.

8. A device for mixing fluids, adapted for immersion in a fluid bath, comprising in combination a central pipe, means for introducing a stream of fluid into one end of said pipe, means at the other end of said pipe for receiving fluid from said pipe and turning it backwardly into a passage formed between the outside of said pipe and a plurality of petticoats, a plurality of petticoats surrounding said pipe and separated therefrom to form said passage therebetween, said petticoats having openings between them through which the immersing fluid may enter said passage and means comprising a central rod passing through said pipe for securing said petticoats together.

9. A device for mixing fluids, adapted for im-

mersion in a fluid bath, comprising in combination a central pipe, means for introducing a stream of fluid into one end of said pipe, means at the other end of said pipe for receiving fluid from said pipe and turning it backwardly into a passage formed between the outside of said pipe and a plurality of petticoats, a plurality of petticoats surrounding said pipe and separated therefrom to form said passage therebetween, said petticoats having openings between them through which the immersing fluid may enter said passage and means securing said petticoats together, said petticoats having internal ribs, the end of one petticoat bearing against the rib of an adjacent petticoat.

10. A device for mixing fluids, adapted for immersion in a fluid bath, comprising in combination a central pipe, means for introducing fluid into one end of said pipe, a base member at the other end of said pipe for receiving fluid from said pipe and turning it backwardly into a passage formed between the outside of said pipe and a plurality of petticoats, a plurality of petticoats surrounding said pipe and separated therefrom to form said passage therebetween, said petticoats having openings between them through which the immersing fluid may enter said passage, an outwardly flared baffle secured to said pipe at the other end of said petticoats from said base member and receiving fluid from said passage and discharging it into the immersing bath and a central rod engaging said baffle and said base member and clamping said petticoats between said baffle and base member.
